ALAN P. BEEBE, OF DETROIT, MICHIGAN, ASSIGNOR TO THE PENINSULAR GRINDING WHEEL COMPANY, OF DETROIT, MICHIGAN, A CORPORATION OF MICHIGAN

GRINDING WHEEL

Application filed September 22, 1930. Serial No. 483,618.

The invention relates to grinding wheels of that type in which a flat disk of the abrasive material is secured to a revoluble metal backing plate. It is the primary object of the invention to obtain a greater strength both in the wheel and its attachment to the backing plate and to this end the invention consists in the construction as hereinafter set forth.

In the drawings:

10 Figure 1 is a section through the abrasive wheel and the backing plate to which it is to be attached;

15 Figure 2 is an elevation of the reinforcement for the abrasive member with the securing sockets attached thereto.

In the present state of the art abrasive grinding wheels have been provided with metallic reinforcements imbedded therein to increase the tensile strength and to resist the 20 tendency to rupture under centrifugal force. With face grinding wheels it is also customary to imbed securing nuts in the plastic material which form the anchors engaged by the clamping bolts for securing the abrasive element to the metallic backing. In my improved construction I combine these features 25 in such a manner as to increase their efficiency in performing both functions. This is accomplished by welding or otherwise rigidly securing to an open mesh metallic enforcement 30 a series of nuts or anchors and subsequently imbedding the reinforcement and anchors in the plastic material from which the grinder wheel is formed.

35 In detail, A is an open mesh metallic reinforcement and B are the nut members provided with a central threaded aperture C and a tapering or wedge shaped peripheral portion. In combining these elements, the nuts

40 B are first positioned in proper relation to each other and the member A is then secured thereto, preferably by welding as indicated at the points D. The combined element is then imbedded or molded into the abrasive body E so that the rear faces of the nuts B lie flush with the face of the abrasive body. This will permit of attaching the wheel to the 45 backing disk F by a series of bolts G.

With the construction as described, the metallic reinforcement serves to distribute the

stresses from the individual nuts B into the whole body of the wheel. On the other hand, as the nuts B are clamped to the backing plate F stresses developed by centrifugal action are resisted not only by the tensile 55 strength of the reinforcement A but also by its attachment to said backing plate. Thus the whole structure is much stronger than one in which the securing nuts and the reinforcing member are not rigidly connected.

60 What I claim as my invention is:

1. In a grinding wheel, the combination of an open mesh metallic reinforcement, an anchor member rigidly attached thereto and an abrasive body in which both of said members 65 are imbedded.

2. In a grinding wheel, the combination of an open mesh metallic reinforcing member, a plurality of anchor members rigidly attached thereto and an abrasive body in which 70 all of said members are imbedded.

3. In a grinding wheel, the combination of an open mesh metallic reinforcing member, a series of anchor members welded thereto 75 and an abrasive body in which all of said members are imbedded.

4. A grinding wheel comprising an abrasive body, an open mesh metallic reinforcing member and a series of anchor members welded to said reinforcing member and imbedded therewith in said abrasive body.

5. A grinding wheel comprising an abrasive body, an open mesh metallic reinforcing member and a series of nuts welded to 80 said reinforcing member in predetermined relation to each other and together therewith imbedded in said abrasive body.

In testimony whereof I affix my signature.

ALAN P. BEEBE.
